UNITED STATES PATENT OFFICE

JACQUE C. MORRELL, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

REFINING AND PURIFICATION OF HYDROCARBON OILS

No Drawing.

Application filed March 25, 1926. Serial No. 97,461.

This invention relates to improvements in refining and purification of hydrocarbon oils, and refers more particularly to the desulphurization of hydrocarbon oils for the purpose of providing a product which is free of refractory sulphur compounds.

The present invention contemplates the refining and purification of hydrocarbon oil of any gravity from a crude hydrocarbon of low 10 gravity, up to and including a motor fuel of higher gravity. More specifically, the invention is peculiarly applicable to the desulphurization of cracked distillates. Hydrocarbon oils, particularly the overhead condensed 15 products sold commercially and produced in cracking operations sometimes contain an objectionable amount of refractory sulphur compounds which are not removable from the oil by the usual refining agents such as 20 sulphuric acid, caustic soda, litharge in caustic soda, filter earth and the like.

I have found that the alkyl-disulphides and analogous sulphur compounds present in oils, may be converted into compounds 25 which can be removed by subsequent subject- 70 tion to treatment with the usual refining agents.

More specifically, I have found that when 30 oil containing these objectionable and refractory sulphur compounds is treated in the presence of a finely divided metal and an oil soluble acid, that these compounds are converted into compounds such as hydrogen sulphide and the mercaptans which can be 35 subsequently treated so as to reduce the total sulphur content of the resulting product.

I have further found that among the metals, which can be used, may be listed zinc, tin, iron or metal having analogous characteristics. Among the oil soluble acids which 40 may be used, may be listed glacial acetic acid and hydrogen chloride.

Either the metal or the acid can be introduced into the oil initially followed by the 45 other, or they may be introduced simultaneously. The oil body into which the refining agents of the present invention have been introduced, is preferably heated since it has been found that the reaction proceeds 50 at a much greater rate under heat than in

the cold. It is further to be noted that in some instances, the oil body containing these refining agents may be agitated for the purpose of securing a more complete intermingling of the various constituents. It is also 55 preferable that the oil being treated under heat, is preferably refluxed or distilled with the refining agents for the purpose of extending the period of reaction by preventing the more volatile components from leaving 60 the system.

The following proportions may be given as illustrative, it being understood that they 65 may vary within wide limits and not depart from the scope of the invention; From 1 to 2% of acid and 1 to 2% of metal based on the volume of oil being treated. It will be found that the reaction taking place in the oil due to the introduction of the reagents of the present invention will convert the refractory sulphur compounds, particularly 70 the disulphides, into compounds which can be subsequently easily treated with the usual refining agents such as plumbite solutions.

The desulphurization as described above, 75 may constitute the sole refining action on the oil, or it may constitute but a step in a series of various refining methods. It may be preceded by the usual treatments with refining agents such as sulphuric acid, caustic soda, 80 plumbite, filtering earth or the like, and may be succeeded by any combination of the above refining agents followed if desired, by distillation.

When using glacial acetic acid, the excess 85 of the latter is removed if any subsequent treatments are given, or if desirable, a subsequent alkali treatment may be applied to remove same.

I claim as my invention:

1. A step in a method of purifying and refining hydrocarbon oils, comprising subjecting the oil to heat in the presence simultaneously of added metal and glacial acetic acid to convert the refractory sulphur compounds in the oil. 90

2. A step in a process of refining and purifying hydrocarbon oils, comprising subjecting the oil to heat in the presence simultaneously of zinc and glacial acetic acid to 100

convert refractory sulphur compounds present in the oil.

3. A step in a method of refining and purifying hydrocarbon oils, comprising subjecting the oil to treatment in the presence simultaneously of added metal and acetic acid.
